UNITED STATES PATENT OFFICE.

CHARLES E. EDGAR, OF KANSAS CITY, MISSOURI.

CAN-FILLER.

1,025,383.

Specification of Letters Patent.

Patented May 7, 1912.

Application filed April 3, 1911. Serial No. 618,701.

To all whom it may concern:

Be it known that I, CHARLES E. EDGAR, a citizen of the United States, residing at Kansas City, in the county of Jackson and State of Missouri, have invented certain new and useful Improvements in Can-Fillers, of which the following is a specification.

This invention relates to can fillers and has for its object to produce a device of this character for automatically supplying water to a can, into which it is inserted, until the water attains a predetermined level and then automatically cut off such supply of water. A further object is to produce a can filler of simple, strong, durable and inexpensive construction embodying few parts and no packing requiring frequent or occasional renewal or adjustment. With these objects in view and others as hereinafter appear, the invention consists in certain novel and peculiar features of construction and organization as hereinafter described and claimed; and in order that it may be fully understood reference is to be had to the accompanying drawing in which—

Figure 1, is a central vertical section on the line I—I of Fig. 2. Fig. 2, is a plan view on a reduced scale, and in dotted lines also showing a can receiving the filler. Fig. 3, is an enlarged section on the line III—III of Fig. 1.

In carrying out the invention, a nozzle is employed consisting preferably of an elbow 1, having an enlargement forming a valve chamber 2, which is internally threaded at 3, at its lower end, a casing 4, screwed at its upper end into the enlargement so that its upper end shall constitute an upwardly-disposed valve seat, an upright tube 5 screwed at its upper end into the lower end of the casing, and a casing 6 secured to the lower end of the tube 5, and provided with depending feet 7.

To support the nozzle in a substantially upright position when arranged in a can, hereinafter referred to, it is provided with a skeleton frame consisting of a pair of diametrically opposite outwardly-bowed rods 8, and a pair of diametrically opposite outwardly-bowed rods 9, the distance between the most remote parts of said rods 8 and 9 respectively, corresponding approximately to the distance between the opposite corners of the can and the opposite side

walls thereof, and the ends of said rods are secured as shown or in any other suitable manner, in external sockets 10, of the enlargement of the elbow, and external sockets 60 of a collar 11 secured on tube 5, at a suitable distance from the lower end of said tube.

Secured on the tube a short distance above collar 11 is a collar 12, and fitting around the tube and upon said collar is a cushion, 65 in the form of a spring 13.

Fitting slidably on the tube and normally resting on the cushion 13 is a sleeve 14 equipped with a float 15 of spherical form, preferably, as shown. Clamped upon 70 the tube above the float is a collar 16 and pivoted at its lower end to said collar is a link 17, pivotally connected at its upper end to a curved crank-arm 18 projecting from one end of a rock shaft 19, arranged horizontally within casing 4 and journaled in sleeve bearings 20 and 21 formed integral with casing 4. The inner end of bearing 20 is formed with a tapered seat 22, and the outer end of the bearing sleeve 21 is closed 80 to form a pocket containing an expansive coil spring 23, exerting endwise pressure on the rock shaft.

Secured on the rock shaft between said bearings is a bifurcated crank arm 24 85 tapered at one end to constitute a bearing 25, held in engagement with the seat 22, by the pressure of spring 23, this pressure being augmented when a can is being filled, by the pressure of the water passing downward 90 through the nozzle on the opposite side of the crank arm as will be readily seen by reference to Fig. 3, so that it will be impossible for a leakage of water to occur between the bearing and its seat 22.

Pivoted on a pin 26 carried by the bifurcated crank arm 24, is a lift rod 27, for raising valve 28 from the upwardly-disposed valve-seat hereinbefore mentioned, the valve being preferably formed with a centrally-disposed downwardly-opening socket 29 receiving the upper end of the lift rod.

The casing 6 is provided with a perforated bottom or spider 30, and secured thereon is a compressible ring 31 forming 105 an upwardly-disposed seat for a reciprocating valve 32, said valve having a central stem 33 fitting slidably in the perforated bottom or spider and of length to project a substantial distance below the same, and the 110 feet 7, when said valve 32 is closed. It will be apparent that under ordinary conditions

the valve 32 is closed by the force of gravity and that the weight of the float maintains the valve 28 in elevated position.

When a can such as indicated by dotted lines 34, is to be charged with water, a flexible hose 35 or its equivalent, is secured on the elbow of the nozzle. The filler is then lowered into the can with the frame disposed substantially as shown in Fig. 2, so as 10 to maintain the nozzle in an upright position. Before the feet 7 engage and arrest the downward movement of the filler in the can, the stem of valve 32 comes in contact with the bottom of the can and effects the 15 unseating of said valve. The instant this occurs water escapes from the tube between the feet 7.

When the water level rises to a predetermined level, the float is raised and in moving upward effects the depression of the lift rod 27 to permit the valve 28 to be forced and held upon its seat by the water in the nozzle above said valve. When another can is to be filled, the person in control 20 lifts the filler out of the can, the valve 32 closing under the pressure of the water standing above it in the nozzle, before the 25 gravitational action of the float occurs whereby the reëlevation of valve 28 is effected. 30 It will thus be seen that the valve 32 is closed before the valve 28 is reopened and that the parts remain in this position until the valve 32 is again reopened, it being obvious, of course, that it must not be opened 35 as long as the supply hose is connected to the upper end of the nozzle, except by the bottom of the can being charged with water, and it will also be noticed that no shock or jar attends the gravitational action of the 40 float as the downward movement of the latter is cushioned by the spring 13.

From the above description it will be apparent that I have produced a can filler possessing the features of advantage enumerated as desirable and I wish it to be understood that while I have illustrated and described the preferred embodiment of the invention I do not wish to be restricted to the exact details of construction shown and described as obvious modifications will suggest themselves to one skilled in the art. 45 50

I claim:

1. In a can filler, a nozzle provided with an internal valve seat and a pair of alined bearings one of which is closed to prevent the escape of water therethrough, a rock shaft journaled in said bearings and projecting completely through one of them, a crank arm secured on said shaft between said bearings and within the nozzle, means for preventing water escaping from the nozzle through the bearing through which the shaft completely projects, a valve in the nozzle for engagement with said seat, a float connected to the said projecting end of the shaft to rock the same, and means movable with the crank arm to unseat the valve when the float moves downward. 55 60 65

2. In a can filler, a nozzle provided with an internal valve seat and a pair of alined bearings, one of which is closed at its outer end, a rock shaft journaled in said bearings, a crank arm, secured on said shaft between said bearings and within the nozzle, a spring exerting pressure to hold the crank arm 70 with a water tight joint against the inner end of the open bearing, a valve, a float connected to the outer end of the shaft to rock the same, and means connected to the crank arm to unseat the valve when the float 75 moves downward. 80

3. A nozzle embodying a casing having alined sleeve bearings communicating at their inner ends with the interior of the casing, and one of them opening through the side of the casing at its outer end and the other closed at its outer end, a rock shaft journaled in said sleeve bearings, a crank shaft secured on said shaft between said bearings, and a spring fitting in the bearing having its outer end closed and exerting pressure against the same and the adjacent end of the shaft to hold the crank arm against the inner end of the other bearing with a watertight relation. 85 90 95

In testimony whereof I affix my signature, in the presence of two witnesses.

CHARLES E. EDGAR.
